UNITED STATES PATENT OFFICE.

ALBERT MARING, OF MUSKEGON, MICHIGAN, ASSIGNOR TO MARING WIRE COMPANY, OF MUSKEGON, MICHIGAN, A CORPORATION OF MICHIGAN.

WIRE-COVERING MACHINE.

Application filed May 25, 1923. Serial No. 641,381.

To all whom it may concern:

Be it known that I, ALBERT MARING, a citizen of the United States, and a resident of Muskegon, in the county of Muskegon 5 and State of Michigan, have invented certain new and useful Improvements in Wire-Covering Machines.

This invention relates to improvements in wire covering machines, and more particularly to machines used in the manufacture 10 of cotton or silk insulated wire, wherein the insulating material is wound onto the wire as it is advanced through the machine. While machines of this character are more 15 or less of a standard construction, there are elements of such machines that admit of improvement in construction and design, and it is to one of these elements that the present invention pertains. For lack of a better 20 term, the element contemplated by this invention may be termed the nose-piece, and designates that element of the machine which guides the yarn onto the wire and controls the winding operation.

25 The object of the invention is to provide an improved construction for nose-pieces with a view of overcoming certain disadvantages in the design heretofore adopted by the machine manufacturers. The principal disadvantages to be overcome arise 30 through the rapid wear and depreciation of the parts of the nose-pieces, thereby requiring frequent replacement and renewal. Furthermore, to accommodate the various sizes 35 of wire, the present practice requires a series of different sized nose-pieces for each machine, thereby increasing the initial cost as well as the cost of maintenance. The construction contemplated by this invention is 40 therefore primarily intended to permit the ready removal of the parts subjected to wear so that they can be refinished for further use, and furthermore by the interchangeability of a single part, the same nose-piece 45 can be employed for a given range of wire sizes.

In the drawings is illustrated a preferred embodiment of the invention, together with such parts of the ordinary form of wire 50 covering machine which would enable the operation to be clearly understood.

Fig. 1 is a view in vertical section showing those parts of a machine which co-operate with the nose-piece in the covering 55 of a single wire.

Fig. 2 is an enlarged detailed view in vertical section of the nose-piece removed from its supporting spindle.

Fig. 3 is a detailed view in cross-section of the nose-piece taken on the line 3—3 of 60 Fig. 2, and Fig. 4 is a similar detailed view in cross-section taken on the line 4—4 of Fig. 2.

Fig. 5 is a perspective view of one of the smoothing blocks forming a part of the 65 nose-piece.

Fig. 6 is a perspective view of one of the clips which serve to retain the smoothing blocks in position; and

Fig. 7 is a perspective view of the removable wire-guiding spindle of the nose-piece. 70

Referring to Fig. 1, a single spindle of a machine is shown in detail, together with more diagrammatic representations as to the means employed for delivering the wire to 75 and from the spindle. Bearing in mind that a single machine may consist of a plurality or battery of spindles, each spindle is constructed as follows: A supporting yoke (1) is mounted upon an angle member 2 forming 80 part of the machine frame, and is arranged in a vertical position. The yoke supports, by means of bearings 3—3, a vertical hollow spindle 4. The bearings 3—3 are journalled in suitable bearing retainers 5—5, formed in 85 the ends of the horizontal arms of the supporting yoke 1, the lower bearing being in the nature of a step bearing and supports the lower end of the spindle 4. Keyed to the spindle 4, just above its lower end, is 90 a mitre gear 6, which meshes with a complementary mitre gear 7, whereby rotative movement in either direction is transmitted through a shaft 8 to the spindle 4. The spindle extends some distance vertically 95 above the supporting yoke 1, and immediately above the upper bearing 5, is mounted, what is termed a flyer 10, which rotates with the spindle, and serves as a guide for the yarn as it is fed from the spool 11 mounted immediately above. This spool consists of 100 the usual core 11a, which fits onto a spool-carrier 12, likewise mounted on the spindle and resting on a fibre washer 13, separating the carrier and the flyer 10. Immediately 105 above the carrier is a fibre collar 14 yieldingly held against the upper end of the carrier by means of a coiled spring 15. At the upper end of the spindle is a pair of removable collars 16 and 17, provided with 110

set screws 16^a and 17^a, respectively, the lower one forming a shoulder for the spring 15, in addition to performing their principal function of anchoring the nose-piece 18 in a 5 socket formed in the extreme upper end of the spindle 4.

The machine is provided with a suitable drum or spool 19, from which the wire to be covered is supplied, the same being led 10 around a sheave 20 located below the spindle 4, and thence upwardly through the central bore of said spindle, through the nose-piece, thence around a sheave 21, and finally to another drum 22, onto which the covered 15 wire is wound.

Consider now a single strand of the wire A as being continuously advanced upward through the spindle, and at the same time a strand of the yarn B as being taken from the 20 spool 11 and guided through suitable eyelet guides 23 secured to the upstanding arm 10^a of the flyer, and thence to the nose-piece where it is wound or wrapped about the 25 advancing wire as the spindle, flyer and nose-piece are rotated at a high rate of speed.

Referring in more detail to the construction of the nose-piece, the same consists of a body in the form of an annular disk or 30 base plate 24, from which depends a tubular sleeve or shank 25, adapted to fit within a socket formed in the upper end of the spindle 4, and securely held in place by means of the collars 16 and 17. A fibre 35 washer or collar 26 is preferably interposed between the under side of the base plate 24 of the nose piece and the upper end of the spindle 4.

Fitting snugly within the tubular sleeve 25 40 and held by a set-screw 25^a, is a removable wire guiding spindle or die 27, having the form of a cylinder with a central bore 27^a of substantially the diameter of the bare wire to be covered. The die projects above 45 the base-plate 24, with parts of the exposed or projecting portion cut away in such a manner as to form a gradually deepening axial groove 27^b and a transverse groove 27^c, thus leaving a portion of the central 50 bore exposed, as clearly shown in Fig. 7. Extending vertically from the base-plate 24 are two arms 28, 28 located in diametrically 55 opposed relation on either side of the projecting end of the die 27, and forming a bifurcated support for other elements presently to be described. The outer faces of 60 these arms are slotted longitudinally to form deep channels 29, 29, extending through the base plate 24 and terminating at the level of the upper end of the die 27. The upper 65 ends of the arms above the die 27 are likewise slotted, but horizontally, thereby forming wider channels 30, 30, connecting with the vertical channels 29, 29. Mounted within the horizontal channels 30, 30, are metal

blocks 31, 31, adapted to slide transversely therein, their inner faces being brought together and into contact with the wire immediately above the end of the die 27, as clearly shown in Fig. 2. Extending over the ends of the slotted arms 28, 28 are clips 32, 32, which form a closure for the upper ends of the slots or guide-ways for the blocks 31, 31 and serve to retain the same against a vertical displacement. These clips are secured in place by means of small screws 32^a, passing through the ends of the clips and anchored in the sides of the arms 28, 28. 75

Located within the vertical slots 29 are flat springs 33, which are anchored at their lower ends by means of screws 33^a, and bear at their free ends against the outer faces of the blocks 31, 31. Intermediate their ends, and nearer their lower ends are set screws 34, which bear against the springs, and are 85 adapted to be adjusted to vary the tension exerted by the springs against the blocks 31 to force them into contact with the wire. 90

Bearing in mind that the wire strand A is advanced upwardly through the spindle 4 and nose-piece 18, and at the same time and that these parts together with the flyer 10, are rotating rapidly, it will be seen that by guiding the strand of yarn B through the eyelets 23 of flyer 10 and thence to the nose-piece it is guided to the wire, and thus wound or wrapped about it, as the non-rotating wire advances through the nose piece. As clearly shown in Figs. 2 and 4, the strand of yarn is led around a vertical guide-pin 35 anchored in the base-plate 24, and thence radially inward toward the wire-guiding spindle, passing through the transverse groove 27^b and around the wire A, the yarn being tightly and evenly wrapped about the wire as it advances from the die 27 and between the blocks 31, 31. The function of the blocks 31, 31 is to apply pressure to the covered wire as it leaves the wire-guiding spindle and thereby to smooth the yarn so that the surface is even and presents a uniform finished surface. 100

Due to the pressure exerted by the blocks, as well as the friction, the metal although hardened, becomes rapidly grooved and thence necessitating the removal of the blocks and the grinding of the contact faces, to remove the groove. In the ordinary nose-piece, the block or blocks for this purpose are of irregular contour and of a spherical design, thereby necessitating the replacement of the block by the manufacturer with the attendant loss of time. Moreover, the blocks herein disclosed are of a regular shape, and hence may be readily provided from ordinary stock, in the event that they become so worn as to require replacement. In short, the use of a simple rectangular form of block which may be readily removed, makes it unnecessary for 115 120 125 130

the machine user to depend on the manufacturer to replace parts of a special design where such parts are subjected to rapid wear.

5. And further, an important feature of the present construction is the provision of a removable, and therefore interchangeable set of wire-guiding dies 27, all having a standard outside diameter but varying in 10 size and formation of the central bore 27a. In this manner, the user of a machine need not maintain on hand a separate nose-piece for each size of wire to be covered but employs a single nose-piece for all sizes 15 of wire to be covered substituting only the required size of wire-guiding spindle or die, which may be secured at a comparatively low cost.

This advantage is an important one, not 20 only as providing for the interchange of dies for various wire sizes, but the interchange of dies for either direction of rotation of the spindle, since successive layers are applied to the wire, by reversing the 25 direction of rotation of the spindle and associated parts.

From the foregoing it will be seen that the departures in construction are exceedingly advantageous from the standpoint of 30 the decreased cost in machinery equipment, as well as of replacements and renewals.

Having set forth the features of the invention, I claim:

1. In a machine of the character described, the combination with a rotative spindle, of a nose-piece comprising a tubular shank fitting in the end of said spindle, a cylindric die removably fitting in said shank and having a central bore through 40 which a strand of wire is advanced, and smoothing blocks mounted for yielding engagement with said wire.

2. In a machine of the character described, the combination with a rotative spindle and spool carrier thereon, of a nose-piece comprising a body having a shank fitting into the end of said spindle, and a central bore extending axially thereof, a cylindric wire-guiding die removably fitted into said bore and having an end portion projecting above said body, and blocks 50 slidably mounted in said body above the end of said die, and means for yieldingly forcing said blocks toward each other.

55. 3. In a machine of the character described, the combination of a rotative spindle, a nose-piece mounted at the end of said spindle and comprising a body having an axial bore therethrough, a cylindric die

removably secured in said bore, and blocks 60 slidably mounted in said body and adapted to yieldingly engage the wire immediately beyond the end of said die.

4. In a machine of the character described, the combination with a rotative 65 spindle, of a nose-piece mounted at the end of said spindle and having an axial bore therethrough, a cylindric die removably mounted in said bore and having a central bore through which a wire is advanced, 70 means for guiding a strand of yarn to the wire in passing through said die, and blocks mounted adjacent the end of said die and supported to yieldingly engage opposite 75 sides of said wire.

5. In a machine of the character described, the combination with a rotative spindle and spool carrier thereon, of a nose-piece comprising a body having a central bore extending axially thereof, a cylindric 80 wire guiding die removably fitted into said bore, and a pair of blocks slidably mounted on opposite sides of said body and adapted to engage the wire leaving said die, and springs engaging said blocks for yield- 85 ingly forcing said blocks against said wire.

6. In a machine of the character described, the combination of a spindle, a nose-piece mounted on said spindle and comprising a shank, a body having a central bore, a cylindric die removably mounted in said bore and having an end portion projecting above said body, arms extending parallel with the projecting portion of said die, transverse channels in said arms, blocks 90 95 slidably mounted in said channels and adapted for bearing contact with the wire leaving said die, and springs engaging said blocks.

7. In a machine of the character described, the combination of a spindle, a nose-piece mounted on said spindle and comprising a body having a tubular shank, fitting in the end of said spindle, a cylindric die removably mounted in said shank 100 and having an end portion projecting above said body, arms arranged on opposite sides of said body and provided with transverse channels at the ends thereof, blocks 105 slidably mounted in said channels and adapted for contact with the wire leaving said die, and flat springs anchored at the base of said arms and engaging said blocks at their 110 free ends.

In witness whereof, I hereunto subscribe my name this 21 day of May, A. D., 1923.

ALBERT MARING.
